GOLF CLUB GRIP

James Victor East, Longmeadow, Mass., assignor
to A. G. Spalding & Bros., New York, N. Y.,
a corporation of New Jersey

Application May 25, 1935, Serial No. 23,497

1 Claim. (Cl. 273—81)

This invention relates to golf club grips and provides a grip which induces proper grasping of the club by a player and a correct stance. The combination thereby establishes the most effective measure of positioning the combined muscular forces for their maximum effort in striking the ball. The grip adapts itself to the player so that the club becomes more in the nature of a part of the player instead of a mere accessory to him.

A player, in angularly tilting his body to correctly grasp a golf club, necessarily rotates his hands from a normal position. An object of the invention is to provide a grip which accommodates this rotational displacement of the hands.

Due to the angular positioning of the club across the palm and fingers, the hands in closing upon the grip assume a conical internal formation. This grip accommodates the conformation of the hands when they are closed thereon.

Another object of the present invention is to set up against the sense of touch through the grip a feeling as to the positioning of the striking face of the club by utilizing the sensitiveness of partly the palm and partly the front side of the fingers of the lowermost hand.

Another object is to compensate for the enlargement of the upper end of the grip to accommodate the portion of the hand grasping that part of the shaft.

Another object of the invention is to provide a golf club grip which will resist the tendency, noticeable in grips of ordinary construction, of the shaft to turn in the hands of the player.

A further object is to provide a grip which, aside from its general taper, will resist the tendency of the club to slip endwise in the player's hands.

Other objects of the invention will be clear from the following description.

The invention is shown in the accompanying drawing, in which:

Fig. 1 is a front view of a golf club embodying the invention, the head being shown as a driver, though it will be understood that the type of head forms no part of the invention.

Fig. 2 is a transverse section of the shaft and grip on line A—A of Fig. 1.

Fig. 3 is a cross section on line B—B of Fig. 1.

Fig. 4 is a cross section on line C—C of Fig. 1.

Fig. 5 is a cross section on line D—D of Fig. 1.

Fig. 6 is an enlarged longitudinal section of the upper portion only of the grip in a plane extending from right to left of Fig. 1 through the axis of the shaft.

Fig. 7 is an enlarged section taken similar to Fig. 6, of the central portion of the grip.

Fig. 8 is an enlarged side elevation of Fig. 7 taken a quarter turn therefrom.

Fig. 9 is an enlarged longitudinal section of the grip and shaft in a plane at right angles to the plane of section in Fig. 6.

Generally considered, the features of the present invention involve the ridge 13 along the under side of the grip, the flattened face 15 on a lateral side of the grip, and the recesses 18 and 19 at the upper portion of the grip.

The grip of the present invention is applied to a club shaft 10 which may be of any standard construction. As here shown, the shaft is of the hollow steel variety, but the invention is not limited to this type of shaft. The grip may be made up of an internal moldable compound 11 as for example finely divided rubber and cork, and an external wrapping or cover 12. The major portion of the moldable layer 11 is concentric with the steel shaft and is of gradually decreasing thickness downward so as to produce a tapered grip. The variations from this general conformation of the grip will be hereinafter noted. In forming these variations, the moldable compound is either thickened to build up an enlargement or it is thinned to form a recess relative to the general conformation. The wrapping 12 when applied to the molded formation conforms thereto so as to produce the final grip of desired shape and size.

The ridge 13 extends lengthwise of the shaft and along the underside thereof. By the underside of the shaft is meant that side which is opposite to the side from which the head of the club extends or, differently stated, is the underside of the shaft when the club is in position addressing the ball. A diametrical plane passing centrally through this ridge is displaced 8 degrees from a diametrical plane passing centrally through the upper and under sides of the shaft. This ridge is placed 8 degrees leftward of the center line of the under face of the grip for a right handed player, or is placed 8 degrees rightward of this center line for a left handed player.

The ridge is offset in this manner to conform to the changes from normal occasioned in the positioning of the hands in grasping the club. That is, it has been found that the angular tilting of the body so as to bring one hand lowermost upon the grip results in a rotation of the hands about the grip to the extent of 8 degrees. By placing the ridge 8 degrees off center in the direction of rotation of the hands, the ridge

passes centrally across both hands. The desired feel that the ridge is lowermost in the hands is thus maintained.

The ridge is of blunt formation and this is effected by its general convex formation. The apex is smoothly rounded off and the sides 14 leading up to this rounded apex are curved outwardly and gradually merge into the normal curvature of the grip. As a result the grip is comfortable in the hand since there are no sharp edges or depressions to which the flesh of the hand has to conform. Furthermore, a greater surface contact is had between the grip and hands and a more equal distribution of pressure results.

The ridge is of greatest height at the upper end of the grip and by gradually decreasing in height downwardly along the shaft, merges into the general formation of the grip at the lower end thereof. As a result, the ridge itself has a taper which is additive to the normal taper of the grip. Not only does this increase the resistance offered against slippage of the club through the hands, but the further advantage is had that the ridge comes into fuller contact with the palm of the hand.

The grip is also provided with a flattened face 15 extending longitudinally thereof and positioned on a lateral side of the shaft. The flattened face begins about $4\frac{1}{2}$ " down from the top of the grip and extends downwardly from this point for about $6\frac{1}{2}$ " further. This flattened face is indicated between the points 15-15 and is on the right hand side for a right handed person or is on the left hand side for a left handed person.

While the surface 15 has been defined as a flattened face it preferably is not a plane in its entirety. The central portion 16 of the face is preferably a plane and lies closer to the axis of the shaft than the end portions of this face. As here shown this plane portion lies substantially between the lines 16-16 but the invention is not confined to this relative position of the limits of the plane portion. The plane of this central portion is parallel to the diametrical plane passing centrally through the upper and under sides of the grip and heretofore referred to. It may be noted that the plane of the central portion of the face is perpendicular to the intended vertical plane in which the ball is to travel. In relation to the striking face of the club head, it may be pointed out that the plane of the central portion of the face is parallel to a horizontal line lying in the striking face when the club is in correct position impacting the ball.

Above and below the central plane portion the face 15 merges into the general grip formation. As here shown, due to the considerable inward setting of the plane portion 16, the portions 17 of the face beyond this plane 16 incline or curve outwardly in order to merge into the grip surface, as can be observed from Fig. 7. While the portions 17 are curved longitudinally of the grip, all lines lying in these portions 17 and extending transversely of the grip are parallel to the plane of the face portion 16. Because of this latter relation the general flattened character of the face 15 is maintained. Generally considered, therefore, the entire flattened face 15 bears the relation defined for the central plane portion 16.

The importance of the flattened face 15 lies principally in the fact that it sets up against the sense of feel a sensation of the location of the striking face. The contact of this flattened face 15 against the palm of the hand creates a feeling

as to the location of the striking face throughout the swing of the club. The player has the same sensation of location in striking the ball that he would have if he were directly contacting the ball with the palm or front side of his hand.

The offset relation of the ridge 13 and the flattened face 15 both contribute to the attainment of an accurate impact with the ball. The ridge 13 enables the player to grasp the club and have the feeling that the ridge is lowermost in both hands. This is the initial step in taking hold of the grip. In closing the hands firmly upon the grip as the final step, the player then becomes conscious of the feeling set up by the flattened face and therefore knows the location of the striking face. The full effectiveness of one of these features therefore would not be obtained were the other not present.

The largest portion of the grip, i. e. the upper end, is clasped between the raised portion of the hand commonly referred to as the "heel" and the little finger. Because of the protuberant character of the "heel" portion and the short length of the little finger it is difficult to adequately encircle the grip with the little finger. In arresting the backward swing of the club the little finger is required to exercise a substantial proportion of control and in starting the downward swing of the club the little finger of the uppermost hand is called upon to exert the major pull to set the club in motion. Such a pull cannot be made as effectively if the little finger does not adequately encircle the club. To enable the little finger of the uppermost hand to adequately grasp the club the grip is formed at the upper end with a recess 18 to receive the "heel" of the hand and with a recess 19 to receive the outer pad of the little finger. The recess 18 for the "heel" is the larger and is on the right side for a left handed player or is on the left side for a right handed player. The shallower recess 19 is diametrically opposite from recess 18.

The recesses 18 and 19 extend only part way around the circumference of the grip, and they merge gradually into the general contour of the grip. The seating of the heel of the hand and the finger in these recesses has the added advantage of preventing slippage of the club within the hands both longitudinally and rotationally.

An added advantage of the grip of this invention is that it assists the player to determine the distance location of the club head—i. e., the extension of the club head from the hands—during the power stroke, due to the increased sensing, afforded the hands through the grip, of the degree of flexing of the shaft. That is, the flexing of the shaft under the muscular effort of the hands, is felt by the hands, and the player's consciousness of the relation between the muscular effort made and the resulting flex of the shaft, informs him of the position of the club head. The present grip, by transmitting these factors to the hands in an improved manner contributes to greater accuracy in play.

While any desired composition may be used for the moldable portion 11 of the grip a satisfactory recipe for a cork-rubber compound is:

	Parts
Rubber, smoked sheet.....	100.0
Zinc oxide.....	4.0
Mercaptobenzothiazole.....	0.5
Sulfur.....	3.0
Granulated cork.....	150.0

First break down the rubber on a cool mill for 75 minutes.

Next add the next three ingredients, mixing well on the mill.

Then add the cork gradually, with rolls sufficiently open to avoid crushing the granules and 5 too much heat.

Mill until the cork is thoroughly incorporated.

To apply to the shaft, roll the compound to a thin sheet, coat the shaft with a sticky cement, wrap the sheet on to the thickness determined by 10 trial, and cure 10 minutes in the mould at 50° F.

Cool the mold before removing.

This is a continuation in part of the copending application Ser. No. 714,320, filed on March 6, 1934, relating to a golf club grip.

5 While the different sides or faces of the grip may be variously designated, it is thought proper to say that the underside of the grip may be considered that side which faces the player when the club is addressing the ball, the upper side 10 is that which faces in the diametrically opposite direction from the under side, the front side is

that side which faces in the general direction in which the flight of the ball is to take place, and the rear side is that which faces in the diametrically opposite direction from the front side.

What is claimed is:

5 'A golf club having a head and a shaft with a substantially uniformly tapering grip, the major portion of the cross sectional contour of which is circular at all points throughout substantially the whole of the intermediate, or normal, hand 10 engaging part of the grip, and having another section of said contour provided with a rib formed by converging portions substantially tangential to said circle, said point of convergence being located on the under side of the grip, and 15 said contour including a third substantially flat faced section which is located at the back of the grip and extends for a substantial extent lengthwise of the grip.'
